CLAIM

The ornamental design for a quick-release mechanism for securing a tabletop video display, as shown and described.

DESCRIPTION

FIG. 1 is an isometric front, top, and right side perspective view of the quick-release mechanism for securing a tabletop video display.

FIG. 2 is a front view of the quick-release mechanism for securing a tabletop video display.

FIG. 3 is a right side view of the quick-release mechanism for securing a tabletop video display.

FIG. 4 is a top view of the quick-re

securing a tabletop video display; and,
FIG. 5 is a bottom view of the quick-release mechanism for
securing a tabletop video display.
